UNITED STATES PATENT OFFICE.

EDWARD L. YARBROUGH, OF SANTA PAULA, CALIFORNIA.

DESIGN FOR A BROOM-RACK.

49,246.

Specification for Design.

Patented June 20, 1916.

Application filed March 17, 1916. Serial No. 84,984. Term of patent 14 years.

To all whom it may concern:

Be it known that I, EDWARD L. YARBROUGH, a citizen of the United States, residing at Santa Paula, in the county of Ventura and State of California, have invented a new, original, and ornamental Design for Broom-Racks, of which the following is a specification, reference being had to the accompanying drawing, forming a part thereof.

Figure 1 is a perspective view; and Fig. 2 is a front view of a broom rack showing my new design.

I claim:

The ornamental design for a broom rack, as shown.

EDWARD L. YARBROUGH.

Witnesses:

J. C. COWDEN, Jr.,
A. C. COWDEN.
